UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, ENGLAND.

RECOIL AND RUN-OUT GEAR OF HEAVY ORDNANCE.

1,074,541.

Specification of Letters Patent. Patented Sept. 30, 1913.

Application filed December 26, 1912. Serial No. 738,559.

To all whom it may concern:

Be it known that we, Sir ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to 10 the Recoil and Run-Out Gear of Heavy Ordnance, of which the following is a specification.

This invention relates to recoil and run 15 out gear of the hydro-pneumatic type of the kind in which a displacement ram integral with or connected to the piston of the tension recoil brake is employed, and in which the air cylinder of the recuperator is 20 provided with a floating piston.

According to this invention we employ 25 means for removing the pressure of the liquid from the piston of the air cylinder for permitting the gun to be moved inward on its slide under the influence of gravity and for permitting the tension recoil brake to be used as an hydraulic press for running the gun out, these conditions being desirable 30 in order to enable the gun to be maneuvered on its slide for overhaul and inspection or other purposes.

In order that the said invention may be 35 clearly understood and readily carried into effect we will describe the same more fully with reference to the accompanying drawings in which:—

Figure 1 is a sectional side elevation, and Fig. 2 an end elevation with the lower part in section on approximately the line 1, 1 of 40 Fig. 1, of a gun mounting provided with one constructional form of the invention. Figs. 3 and 4 are views similar to Figs. 1 and 2 showing another constructional form of the invention. Fig. 5 is an enlarged view 45 of a part of Fig. 3. Figs. 6 and 7 are views similar to Figs. 3 and 4 showing still another constructional form of the invention.

In all these figures like letters of reference indicate similar parts.

50 A is the gun, B the cradle that recoils with the gun and C the slide frame for the cradle.

D represents the cylinder and D' the piston of the tension recoil brake.

E represents the aforesaid displacement ram.

F represents the air cylinder of the recuperator, F* its floating piston, and f* its rod which projects through the rear wall of the cylinder F.

In the constructional form of the invention shown by Figs. 1 and 2 we provide for the escape of the liquid from the recoil cylinder D into suitable receivers by the inward movement of the gun under the action 65 of gravity when placed at a suitable angle of elevation. For this purpose a stop cock F* is provided in the example shown, by means of which the liquid side of the air cylinder F can be put into communication 70 with a tank or receiver F*, so that when the cock is opened the air pressure acting on the floating piston F* forces the latter rearwardly against its stop f**. As the gun is no longer held in its run out position by the 75 pressure of the air in the cylinder F, the force of gravity causes the gun to move inward, thereby displacing part of the liquid in the cylinder D as a result of the entry 80 of the displacement ram into this cylinder. The displaced liquid passes through a hole or 85 passage f in the cylinder D to the liquid side of the cylinder F and thence past the stop cock F* to the tank or receiver F*. The liquid remaining in the recoil cylinder after the gun has been run in by gravity as aforesaid can then be drained into suitable 90 vessels through the drain cock D** or it can be simply allowed to mix with the water under pressure when the latter is brought 95 into operation for running the gun out as will be now described. In order to effect the running out of the gun, we provide, in the example shown, a passage d* in the piston rod d' of the recoil brake which passage 100 terminates at its rear end at the rear face of the piston D' and at its front end in a pipe d'* which leads to a control valve d**. By means of this valve water under pressure can be admitted to the recoil brake cylinder D for causing the gun to run forward at any desired angle of elevation. To recharge the recoil cylinder the gun is run out and placed at 1° elevation. The stop

valve d^{3x} is closed and the water drained by the drain cock D^{xx} from the recoil cylinder D. The drain cock D^{xx} is then closed and the cylinder partially filled with the special liquid from the receiver F^6 through the stop cock F^4 . The filling of the cylinder is completed by means of the hand pump D^2 through the pipe d^{6x} and the stop valve d^{4x} .

10 In the constructional form of the invention shown by Figs. 3, 4 and 5 we dispense with the usual liquid in the recoil brake cylinder D and use in place thereof water supplied from the main hydraulic pressure system. This arrangement provides a combined system of pneumatic and hydraulic run out, which system enables the maneuvering of the gun on its slide to be effected when desired without the necessity of draining the liquid from the recoil brake cylinder into receivers as described with reference to Figs. 1 and 2. For this purpose we provide in the example shown, a control valve d^{2x} (similar to that above described) 15 connected to the pressure supply of the hydraulic system by the pipe d^2 and with the exhaust by a pipe which is not shown. The casing of the said valve is connected to that of an intercepting valve D^3 by pipes d^3 , d^4 20 of which the former terminates beneath a piston d^{3x} on the valve D^3 and the latter terminates beneath the valve. The port D^{3x} of the valve casing forms a continuation of a passage e in the rear end of the displacement ram, the latter in turn communicating with the cylinder D by suitable holes formed in the side of the said ram. The parts are normally in the position shown in the drawings, and during the recoil and run out of 25 the gun, the water in the recoil brake cylinder D and the air cylinder acts in the same way as the usual liquid, the valve D^3 being retained on its seat to prevent escape of the water. To enable the gun to run in on its 30 slide for inspection purposes as aforesaid, the control valve d^{2x} is moved to admit water under pressure to the pipe d^3 and to place the pipe d^4 to exhaust. The piston d^{3x} accordingly rises, carrying with it the valve 35 D^3 . The interior of the ram E and consequently the cylinders D and F are thereby placed to exhaust and the gun can then run in under the action of gravity. The speed at which the gun is permitted to run in can 40 be controlled, and shocks thereby avoided, by the manipulation of the valve d^{2x} . When it is desired to effect the run out of the gun, the control valve d^{2x} is shifted to the run out position, thereby placing the pipe d^4 and the 45 port D^{3x} to pressure. The stem of the intercepting valve D^3 is, in the example shown, connected to a bell crank lever d^{5x} which in turn is connected by a link d^5 to a lever d^{5x} pivoted to the slide frame. 50 The free end of this lever is disposed in the

path of a stop B^x on the cradle in such manner that as the gun nears its run out position the stop displaces the lever d^{5x} into a position to partly close the valve D^3 and so throttle the supply of water pressure to the cylinder D, thereby avoiding the shock which would otherwise take place as the gun reaches its run out position. By means of this form of the invention the hydraulic apparatus can always automatically maintain the full volume of water in the system whether under ordinary conditions of running out by pneumatic pressure, or when the hydraulic system is in use), for which purpose the control valve d^{2x} is normally retained in the "run out" position so that the water will pass through the intercepting valve to make good any leakage which may, from any cause, take place.

In the constructional form of the invention shown in Figs. 6 and 7 we so construct and arrange the run out gear that it is adapted to effect the run out of the gun, after inspection as aforesaid or after recoil, by means of hydraulic pressure if the pneumatic system should become unintentionally inoperative. For this purpose we provide in the example shown two spring controlled relief or by-pass valves D^4 (Fig. 7) the upper surfaces of which are in communication with the rear end of the hollow displacement ram E. A pipe D^{4x} leads from each of the air cylinders F to the lower ends of the casing of each of the valves. Each of these pipes terminates at its upper end in a hollow rod F^{xx} which passes through the piston rod f^x of the floating piston F^x and also through the piston itself. The lower ends of the valves are provided with pistons D^5 , so that as long as the pneumatic system remains operative the air in the cylinder F acts on the pistons D^5 and assists the spring D^{5x} in holding the valves D^4 on their seats. A control valve d^{2x} and an intercepting valve D^3 such as that described with reference to Figs. 3 and 5 is as shown provided for operating the gun when the hydraulic system is in action. Similarly the mechanism for automatically moving the valve D^3 to throttle the supply of water to the brake cylinder D may also be employed although it is not so shown on the drawings. It will be obvious that if desired we may employ only one valve D^4 instead of two as shown. If the air pressure fails, water under pressure is admitted to the cylinder D by the control valve d^{2x} . The water passes into the cylinder F through the hole or passage f and causes the piston F^x and its rod f^x to move to the right. The cylinders D and F are thus full of water under pressure, and consequently, during the recoil movement of the gun, the water displaced by the ram E opens the valve D^4 and passes to the exhaust port D^6

of the valve casing. We may provide suitable tanks for the discharged water, and from these tanks the water flows by the action of gravity to the exhaust pipe of the 5 hydraulic system.

A non-return valve f' (Fig. 4) may be provided in the hole or passage f between the cylinders D and F, this valve being formed with a by-pass to permit of the 10 gradual return of the liquid from the cylinder F to the cylinder D during the run out movement of the gun.

What we claim and desire to secure by Letters Patent of the United States is:—

- 15 1. In recoil and run out gear for ordnance, the combination with the brake cylinder, the tension brake piston, the displacement ram integral with said piston, the air cylinder and its floating piston, of means for removing the pressure of the liquid from the floating piston to permit the gun to move inward under the influence of gravity.
- 20 2. In recoil and run out gear for ordnance, the combination with the brake cylinder, the tension brake piston, the displacement ram integral with said piston, the air cylinder and its floating piston, of means for removing the pressure of the liquid from the floating piston to permit the gun to move inward under the influence of gravity, and separate means for admitting water under pressure to the brake cylinder.
- 25 3. In recoil and run out gear for ordnance, the combination with the brake cylinder, the tension brake piston, the displacement ram integral with said piston, the air cylinder and its floating piston, of means in the air cylinder for exhausting the liquid therefrom to permit the gun to move inward under the influence of gravity, and separate means for admitting water under pressure to the brake cylinder.
- 30 4. In recoil and run out gear for ordnance, the combination with the brake cylinder, the tension brake piston, the displacement ram integral with said piston, the air cylinder and its floating piston, of a stop cock in the wall of the air cylinder for exhausting the liquid therefrom to permit the

gun to move inward under the influence of 50 gravity, and separate means for admitting water under pressure to the brake cylinder.

5. In recoil and run out gear for ordnance, the combination with the brake cylinder, the tension brake piston, the displacement ram integral with said piston, the air cylinder and its floating piston, of a stop cock in the wall of the air cylinder for exhausting the liquid therefrom to permit the gun to move inward under the influence of 55 gravity, and a control valve for admitting and exhausting water under pressure to and from the brake cylinder.

6. In recoil and run out gear for ordnance, the combination with the brake cylinder, the tension brake piston, the displacement ram integral with said piston, the air cylinder and its floating piston, of a stop cock in the wall of the air cylinder, a receiver in communication with said stop cock, 70 a control valve for admitting and exhausting water under pressure to and from the brake cylinder, and a pump in communication with the brake cylinder.

7. In recoil and run out gear for ordnance, the combination with the brake cylinder, the tension brake piston, the displacement ram integral with said piston, the air cylinder and its floating piston, of a stop cock in the wall of the air cylinder, a receiver in communication with said stop cock, 75 a drain cock in the wall of the brake cylinder, a control valve for admitting and exhausting water under pressure to and from the brake cylinder, and a pump in 80 communication with the brake cylinder.

In testimony whereof we affix our signatures in presence of two witnesses.
